MATERIAL TREATING MECHANISM

Harry E. Vogeli, Alliance, Ohio, assignor to The
Salem Engineering Company, Salem, Ohio, a
proprietorship

Application March 15, 1944, Serial No. 526,588

2 Claims. (Cl. 214—18)

1

This invention relates to the art of material handling and particularly to apparatus for conveying relatively heavy, substantially cylindrical bodies of work at a predetermined rate of speed through a work-treating unit.

An object of the invention is to provide material handling apparatus for moving a relatively heavy, substantially cylindrical body by a reactive force incident to the rotation of the body.

Other objects include the provision of a conveyer for relatively heavy, substantially cylindrical work in which the propelling force is incident to the rotation of the work and the rate of propulsion is dependent upon the arrangement of the work-supporting means; the provision of a conveyer for moving work through a treating unit wherein the work is propelled through said unit by a reactive force incident to its rotation; the provision of such a conveyer for such a treating unit wherein the work-rotating means is remote from the treating unit and unaffected thereby; the provision of a conveyer including articulated driving means extending along the path of work movement which is adapted partially to support and effect rotation of the work, and in which angularly-disposed rotatable discs are adapted to cooperate with the articulated driving means to complete the work support and to advance the work in response to its rotation; the provision of a heat-treating furnace for substantially cylindrical billets within which a conveyer is located for transporting the billets through the furnace at a predetermined rate of speed by the reactive force between a part of the conveyer and the billets and incident to the rotation of another part of the conveyer; the provision of such a heat-treating furnace and conveyer wherein the billet rotating means is located outside of the furnace heating zone; and the provision of discharging apparatus for such a heat-treating furnace.

The above, other objects and novel features of the invention will become apparent from the following specification and the accompanying drawings, in which:

Figure 1 is a top plan view of a heating furnace with its roof removed showing a conveyer and discharging mechanism embodying the principles of the invention;

Figure 2 is a sectional elevational view taken substantially along line 2—2 of Fig. 1;

Figure 3 is a sectional elevational view taken substantially along line 3—3 of Fig. 1;

Figure 4 is a sectional detail view taken substantially along line 4—4 of Fig. 1; and

Figure 5 is a detail view along line 5—5 of Fig. 2.

Although the principles of the invention are applicable to many types of installations wherein it is desired to simultaneously rotate and longitudinally move relatively large, substantially cylind-

2

drical bodies, they are shown and will be described as applied to a billet heat-treating unit.

Referring to the drawings, and particularly Figs. 1 and 2, a relatively long heat-treating furnace F is provided with a conveyer C located therein for simultaneously rotating and longitudinally moving billets B therethrough which are fed to the conveyer C by a charging table T. Power for conveyer C is supplied from a source P located outside of the heating zone of the furnace F. As the billets B complete their travel through the furnace F, they are received by a discharging mechanism D adapted to raise the billets, turn them through 90 degrees and deposit them on an inclined ramp.

Referring to Figs. 1 and 2, the furnace F comprises side walls 10, 11; end walls 10', 11'; a base 12; and a top or roof 13 (removed in Fig. 1 to show the conveyer C). The furnace is of conventional design adapted progressively to apply heat from any suitable source to the billets B as they pass therethrough.

The conveyer C comprises a plurality of substantially aligned tubular members 14, 15 and 16 that are joined together by articulate connectors. The left-hand end of tube 14 (as viewed in Fig. 2), is pinned to a hub 17 of a connector having a flange 18. The other end of the connector is fixed to the hub 19 of a coupling 20, which latter is operatively connected to the source of power P to be described later. The end of tube 14 opposite that pinned to hub 17 is pinned to one ball 21 of a universal connector 22. The left-hand end of tube 15 is pinned to another ball 23 of connector 22, but along an axis at 90 degrees from that of the pin within ball 21. Accordingly, articulation may be obtained between tubes 14 and 15 by virtue of the connector 22. The right-hand end of tube 15 is pinned to a ball 24 of a universal connector 25 by a pin located along an axis at 90 degrees from that of the pin through ball 23. The left-hand end of tube 16 is likewise pinned to a ball 26 of connector 25, the pin being located along an axis at 90 degrees from that of the pin in ball 24. From the foregoing it is evident that tubes 14, 15 and 16 may have slight articulate motion relatively to each other.

The assembly of tubes 14, 15 and 16 is supported by a plurality of anti-friction bearing supports 27, 28, 29, 30, 31 and 32. Each of these bearing supports is identical with the other and, therefore, only one will be described. Referring to Fig. 3, the bearing support 29 comprises a base 33 adapted to be rigidly, but adjustably mounted on the base 12 of the furnace F. Base 33 includes standards 34 and 35, at the upper end of each of which are provided bosses 36 and 37, respectively. The bosses 36 and 37 are slotted at 38 and 39, respectively, for the reception of trunnioned rollers 40, 41. The construction is such that rollers

40, 41 may readily be replaced when worn by simply raising tube 15. The angular relation of the slots in standards 34 and 35 is such that the weight of tube 15 and that of billets B force the rollers 40, 41 into the bearings formed in the bosses of standards 36, 37.

The conveyer C also includes means that is adapted to cooperate with the tubes 14, 15 and 16 to form supporting means for the billets B. This means comprises a plurality of individually supported discs 42, the diameter of which is substantially the same as that of tubes 14, 15 and 16. These discs 42 are provided with trunnions journaled in supporting bearings 43 (Fig. 4) that are adjustably mounted on a base member 44 (Figs. 1 and 3) extending along the path of movement of the billets B and substantially parallel with the tubes 14, 15 and 16. The base 44 may be of any desired construction so long as it provides a support for the bearings 43. The bearings 43 comprise rectangular blocks having two parallel slots 45 in their upper surface adapted respectively to receive one trunnion each of adjacent discs 42. The rectangular blocks 43 are adjustably mounted in parallel spaced relation along the base 44 and at an angle to the tubes 14, 15 and 16. The construction and arrangement are such that the slot 45 nearest the tubes 14, 15 and 16 of one block 43 cooperates with the slot 45 farthest from said tubes in a next adjacent block 43 to support a disc 42. This construction supports the discs 42 such that a plane passing through the discs at right angles to its trunnions is at an angle to the longitudinal axis of the tubes 14, 15 and 16. The blocks 43 support discs 42 at an elevation such that their centers of rotation are substantially the same elevation as those of tubes 14, 15 and 16.

From the foregoing, it is evident that a substantially cylindrical body such as a billet B may be supported between the tubes 14, 15 and 16 on the one hand and the discs 42 on the other hand. The bases 29 and 44 may be separated or moved together, and the diameter of the tubes 14, 15, 16 and discs 42 may be changed to provide optimum conditions for supporting the billets B.

Referring to Fig. 2, the source of power P for propelling the billets B through the furnace F comprises a motor 46 connected through a conventional speed-reduction unit 47 to a coupling 48 adapted to be connected to coupling 20. A pair of rollers 49 is mounted for free rotation and each engages opposite faces of disc 18 to guide the disc 18 and to prevent it from wobbling.

Energization of motor 46 rotates the tube assembly including tubes 14, 15 and 16. Depending upon the diameter of the billet B, the bases 29, 44 are spaced, and the diameters of tubes 14, 15, 16 and discs 42 are such that sufficient friction between the billets B and the tubes 14, 15 and 16 is provided to cause the rotating tubes to rotate the billets B. Furthermore, the rotating billets B react on the discs 42, causing their rotation, and by virtue of their angular disposition, they provide a reactive force on the billets B to move them axially relatively of the furnace F. The angle at which the discs 42 are arranged relatively to the billets B determines the lead or forward feed of the billets for each revolution of the billets. Accordingly, varying the angular disposition of discs 42 and the speed of rotation of tubes 14, 15 and 16 will provide a relatively large range of rates of movement, both rotary and axial, of the billets

B to meet the demands required in treating the work.

The charging platform may be of conventional design and is here shown as an apron 50 on each side of conveyer C located between the entrance to furnace F and power unit P. The aprons 50 are slightly inclined forming a trough, the bottom of which comprises a portion of conveyer C. Accordingly, billets may be loaded from either side of the furnace and when deposited upon the charging platform, gravitate onto the section of the conveyer C ahead of the furnace F.

As the billets B complete their travel through the furnace F, they are fed to an inclined roller conveyer 51 including a base 52 adapted to support a plurality of concavo-cylindrical rolls 53. The conveyer 51 transfers the billets B from the furnace F to the discharge mechanism D.

The discharge mechanism D comprises a work or billet receiver 54 made up of a support 55 adapted to support a plurality of concavo-cylindrical rolls 56 similar to rollers 53. It is provided with an abutting portion 57 at its lowest end against which billets B come to rest when received from the conveyer 51. The receiver 54 is fixed to the free end of a piston 58 that is adapted to be reciprocated within a cylinder 59. The cylinder 59 is fixed against axial and rotary movement within a tube 60. The outer periphery of cylinder 59 is provided with a slot 61 adapted to receive a follower 62 journaled on a trunnion fixed to the periphery of piston 58. Referring to Fig. 5, the configuration of slot 61 is such that movement of piston 58 throughout its working stroke will rotate it and receiver 54 through 90 degrees. The lower end of tube 60 is threaded to receive a plug 63 having a shaft 64 threaded into a boss on a fixed base plate 65. Plate 65 is provided with a vertically-disposed fin 66 rigid with tube 60 for supporting it in operative position. Pressure medium is admitted beneath piston 58 through conduit 67 each time a billet B is received on member 54.

The connection between support 55 and piston 58 includes a hinged joint 69, Figs. 1 and 2. The support 55 also includes an arm or lever 70 extending outwardly beyond hinge 69 and adapted, when the piston 58 approaches its upper position, to contact a fixed abutment 71. Continued upward movement of piston 58 causes support 55 to pivot about hinge 69, thereby effecting the deposit of the billet B onto an inclined slide 72 that conveys the treated billet away from the furnace F.

Although the various features of the material handling and treating unit have been shown and described in detail to fully disclose one embodiment of the invention, it will be evident that numerous changes may be made in such details, and certain features may be used without others, without departing from the principles of the invention.

What is claimed is:

1. Apparatus comprising in combination, a material-treating compartment; means within said compartment including a plurality of aligned tubular members joined together by articulated connectors; a plurality of individually rotatable discs arranged along a path substantially parallel with that formed by said tubular members and each rotatable in an upstanding plane angularly disposed with respect to the principal axis of said tubular members to form with said tubular members supporting means for substantially

cylindrical work pieces adapted to be treated; means for rotating said tubular members; and discharging means located at the exit of said compartment.

2. Conveying apparatus for use in a material-treating compartment comprising in combination an elongated roll extending longitudinally in said compartment, means to support said roll, means to rotate said roll about its longitudinal axis, a plurality of individual disk-like supporting rolls 10 spaced longitudinally along one side of said elongated roll to form a trough-like path for objects to be conveyed, and means mounting said disk-like rolls for rotation in upstanding planes obliquely disposed with respect to said longitudinal 15 axis whereby said objects will be caused to be rotated and simultaneously advanced longitudinally along said path.
